UNITED STATES PATENT OFFICE.

RICHARD H. VESEY, OF IDAHO SPRINGS, COLORADO, ASSIGNOR OF ONE-FOURTH TO GEORGE S. SANDERSON AND WALTER S. SANDERSON, OF DENVER, COLORADO.

TAMPING-PLUG.

SPECIFICATION forming part of Letters Patent No. 650,803, dated May 29, 1900.

Application filed December 14, 1898. Serial No. 699,223. (No model.)

To all whom it may concern:

Be it known that I, RICHARD H. VESEY, a citizen of the United States of America, residing at Idaho Springs, in the county of Clear Creek and State of Colorado, have invented certain new and useful Improvements in Tamping-Plugs; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to a tamping-plug for use by miners and others while blasting. Its object is to facilitate the work of closing the hole in the rock after the charge of giant-powder has been deposited and also to lessen the danger incident to the use of giant-powder in this class of work. After drilling the hole in the rock to the required depth and placing the powder therein the ordinary practice is to insert the cap and fuse and then fill the hole around the fuse with such material, as fine rock and dirt, as may be accessible, this material being tamped tightly in place in order to confine the powder and increase its explosive action. This operation is slow and tedious, and in case of a "missed shot" or the failure of the powder to explode the material tamped around the fuse, as heretofore explained, must be dug out to permit the insertion of a new fuse. This operation is very dangerous and the concussion often explodes the powder, resulting in loss of life or serious injury to those engaged in the work. The object of my improvement is to overcome these difficulties by first obviating the necessity of the tamping operation, as heretofore defined, and, second, by eliminating all danger in case the powder fails to explode as anticipated.

To these ends my improvement consists of the features, arrangements, and combinations hereinafter described, and claimed, all of which will be fully understood by reference to the accompanying drawings, in which is illustrated an embodiment thereof.

In the drawings, Figure 1 is a section taken through the rock, showing my improved tamp-

ing-plug in place preparatory to tightening the device by driving in the shorter plug part. Fig. 2 is a side elevation of the plug, shown in detail and on a larger scale. Fig. 3 is a longitudinal section taken through the same. Fig. 4 is a face view of one of the wedge-shaped parts of the device. Fig. 5 is cross-section taken through the device on the line *x-x*, Fig. 3.

Similar reference characters indicating corresponding parts in these views, let the numerals 5 and 6 designate, respectively, two wedge-shaped coöperating parts which together form a cylindrical or approximately cylindrical plug provided with a longitudinal opening 7, forming a passage-way for the insertion of the fuse and cap.

My improved two-part plug may be formed by boring a hole in a cylindrical piece of wood and sawing through it diagonally, whereby two coöperating inclined engaging faces are formed. This plug may, however, be formed in any suitable manner and of any desired material. When the plug is inserted in the hole in the rock, the part 5 has its larger extremity innermost, while the part 6 has its larger extremity outermost. A piece is cut from the inner extremity of the part 6 to prevent this extremity from projecting into the powder as the said part is driven into the hole. In the inner portion of the opening 7 is located a piece of tubing 8, preferably composed of soft rubber and made of such size as to receive the cap 9 and at the same time form a water-tight joint around the fuse to prevent the water or moisture from reaching the cap. These caps are primed or loaded with fulminate of mercury, and the presence of moisture renders them useless. The part 5 of the plug is provided with a piece of stiff canvas 10, whose edges are secured thereto in any suitable manner, as by the use of glue or other sticky substance. This canvas piece forms a sort of sheath or holder for the part 6 of the plug and connects the two parts temporarily. Hence it is a convenience, and at the same time it increases the friction between the rock and the plug part 6 as the latter is forced into the hole, thus causing it to hold

better and overcoming any tendency to slip backward as it is forced into the hole.

The part 5 of the plug is preferably provided with a tongue 12, whose inner extremity projects outwardly beyond the face of the plug part and engages a center-part 5 recess formed in the part 6 preparatory to driving the part 6 inwardly during the tightening operation. The face of this tongue is beveled, and its outer extremity lies in the plane of the plug-face. Hence the incline of the tongue's face is steeper than the incline of the face of the part 5, and the tongue has therefore a tendency to separate the outer portions of the plug parts as the plug 6 is forced inwardly. This feature is important 10 from the fact that the holes in the rock are usually larger at their outer extremities and diminish in size as they extend inwardly, for the reason that the drill-bit as it is used wears smaller, thus making the hole in the rock of 15 less diameter as it extends inwardly.

In using my improved device the powder 13 is first placed in the hole in the rock. The cap 9 is then put on the end of the fuse 14 and inserted in the hole 7 of the plug until 20 the closed end of the cap is nearly flush with the inner extremity of the plug part 5. When this is done, the rubber tube 8 closes tightly on the fuse outside of the cap, forming a water-tight joint, as heretofore explained. The 25 plug is then inserted in a hole in the rock until the larger extremity of the part 5 is in contact, or nearly in contact, with the powder. The plug is then tightened in the hole by tamping on the outer or larger extremity of 30 the part 6, which moves inwardly until the plug is securely fastened by the wedging action of the two parts. It will be observed that as the part 6 is forced inwardly the part 35 5 remains practically stationary, whereby 40 there is no danger of exploding the powder,

since the inner extremity of the part 6 cannot reach the powder during the operation of plugging the hole. When the explosion takes place, the outward pressure or force applied to the larger extremity of the part 5 of the 45 plug has a tendency to tighten the plug in the hole. Hence the plug can never blow out. In case of a charge wherein the power fails to explode it may be exploded without removing the plug. This is accomplished by 50 exploding a little powder in the hole outside of the plug. In this case the resulting concussion acting on the plug explodes the original charge.

It must be understood that I do not limit 55 the invention to the details of construction herein shown and described, as I am aware that many changes may be made without departing from the spirit of the invention.

Having thus described my invention, what 60 I claim is—

1. A tamping-plug provided with a fuse-opening and comprising two parts having inclined, engaging faces, one part being provided with a tongue having an inclination or 65 pitch greater than that above which it projects.

2. A tamping-plug having a fuse-opening, and comprising two wedge-shaped cooperating parts, and suitable means for temporarily 70 connecting the two parts together, said means comprising a sheath attached to one part and adapted to receive the other part.

In testimony whereof I affix my signature in presence of two witnesses.

RICHARD H. VESEY.
